UNITED STATES PATENT OFFICE.

JOHN C. HANNA, OF CHICAGO, ILLINOIS, ASSIGNOR TO HANNA ENGINEERING WORKS, OF CHICAGO, ILLINOIS, A CORPORATION OF ILLINOIS.

FLUID-ACTUATED MECHANISM.

Application filed February 27, 1922. Serial No. 539,380.

To all whom it may concern:

Be it known that I, JOHN C. HANNA, a citizen of the United States, residing at Chicago, in the county of Cook and State of Illinois, have invented certain new and useful Improvements in Fluid-Actuated Mechanism, of which the following is a specification.

This invention relates to improvements in fluid actuating mechanism and has for its object to provide a mechanism in the nature of a hoist, differentially actuated and especially adapted for the operation of constant weights, as, for example, in the opening and shutting of an oven door, or the like.

The principal object of my invention is to provide a simple and efficient fluid actuated mechanism of this character which will operate for the major portion of its stroke at substantially high speed and for the remaining portion of its stroke at a reduced speed, so that, for example, when a heavy door is operated thereby the same may be permitted to close for the major portion of its movement at a relatively great speed, the closing movement being terminated at a reduced speed to reduce the momentum and obtain substantially a cushion effect at the final closure. It will be appreciated that many uses exist for such a mechanism and I simply cite a specific example for clearness. In the embodiments of my invention shown in the accompanying drawing, I have provided a pair of fluid actuated independently movable pistons of different effective areas, the flow of actuating fluid being restricted in the actuation of one of these pistons in order to provide a differential movement between the two.

These and other objects of the details of the mechanism will be more fully described and shown in the accompanying drawings, in which—

Figure 1 is a vertical section through one embodiment of my invention;

Fig. 1^a is a diagrammatic section of the controlling valve;

Fig. 2 is a side elevation of the form shown in Fig. 1 mounted for one method of use;

Fig. 3 is a similar form shown as mounted for a different method of use;

Fig. 4 is a vertical section of a modification of the invention; and

Fig. 5 is an application of this modified form.

Like numerals refer to like elements throughout the drawings in which 10 designates generally a cylinder having the cylinder heads 10^a—10^b. A duct 10^e is provided in the head 10^a and a duct 10^d in the cylinder head 10^b. A reciprocal piston 11 reciprocally mounted in cylinder 10 is provided with a relatively large piston rod 12 projecting through a stuffing box 13, or the like, being provided with an engageable yoke or strap 14 at its projecting extremity. A second piston 15 is mounted for reciprocation in cylinder 10 as shown in Fig. 1, for example, this piston being provided with a relatively small piston rod 16 extending through the stuffing box 17 in the cylinder head 10^b and provided with base plate 16^a or the like at its outer extremity. As is obvious, pistons 11 and 15 are mounted between the closed ends of the cylinder 10 for independent relative movement, an escape port 10^e being provided in the wall of the cylinder 10 intermediate the pistons 11 and 15.

An actuating fluid supply pipe 25 is provided leading to a three-way valve 26 illustrated diagrammatically in Fig. 1^a, valve control handle 26^a being provided for actuation of the valve. From the valve 26 leads 85 the exhaust pipe 28 which leads into the cylinder 10 between the pistons 11 and 15, as illustrated in Fig. 1. Also leading from the valve 26 is the main supply pipe 29, one branch 29^a leading to port 10^d in cylinder 90 head 10^b and the branch 29^b leading to the port 10^e in cylinder head 10^a. A throttle valve 30 is provided in the branch line 29^a which may be adjusted by a wrench or the like through the medium of stem 30^a to regulate and restrict the flow of the actuating fluid through the pipe 29^a.

In Fig. 2 I have illustrated one method of application of the mechanism shown in Fig. 1, in which the yoke 14 is in engagement with a hook 40 or the like, in a suspending beam 41, a hook 42 being carried by the projecting end of piston rod 16 and in engagement with a weight or the like,

diagrammatically illustrated and designated by numeral 43. In this method of application, assuming the valve 26 to be in full line position shown in Fig. 1^a, the actuating fluid will flow through the branch pipes 29^a—29^b into the respective ends of the cylinder and pistons 11 and 15 will be moved together, the difference in effective area of such pistons partially or substantially balancing the restricted flow of the actuating fluid beneath piston 15. The pistons will be moved to the position shown in dotted lines, in Fig. 2 and full lines in Fig. 1, that is, their innermost limits of travel, and if the valve be maintained in full line position the weight 43 will remain suspended. It should also be remarked that while the exhaust pipe 28 is closed with the type of valve shown, this movement of the pistons will be permitted, due to the escape port 10^c, which will permit sufficiently rapid efflux of the air from between the pistons 11 and 15.

Upon movement of the valve 26 to dotted line position shown in Fig. 1^a, air may escape from the ends of the cylinder into the exhaust pipe 28, therefrom into the cylinder between the pistons and out of the escape port 10^c. Due to the unrestricted flow through pipe 29^b and pipe 29, and due to the lesser effective area of the piston 11, as compared to piston 15, and also due to the restricted outflow of fluid from beneath the piston 15 through the throttle valve 30, when the parts are properly arranged and regulated, piston 11 will complete its stroke in relatively short time and since the piston rod 12 is considerably longer than piston rod 16, the major portion of the travel of weight 43 will be at relatively high speed. As piston 11 completes its outward movement the speed of travel of the weight 43 is checked by the slower travel of piston 15. At the same time, should the momentum of the weight be considerable, it will result in a relatively considerable compression of the actuating fluid beneath piston 15 which may slightly hasten the escape thereof for a brief period of time until the momentum of the moving weight is reduced, with consequent reduction in the compression beneath piston 15. This dropping of the pressure results in the normal restricted outflow through pipe 29^a, its restriction greatly checking or cushioning the final movement of the weight 43, moving the same to rest at a relatively reduced speed with respect to that of the major portion of its movement. The greater effective area of piston 15 results in greater resistance to the movement thereof, as will be apparent.

In the method of use illustrated in Fig. 3, the cycle of operations is similar to that just described, the weight being actuated

through the medium of pulleys and cable, the end of piston 16 being secured to a floor, base, or the like. In view of the similarity of operation no further description of this form is believed to be necessary.

In some instances it is desirable to utilize this mechanism in connection with the direct lift, of a weight, and for that purpose I utilize the embodiment illustrated in Figs. 4 and 5 of the drawings in which an upper small cylinder 100 is provided and a lower large cylinder 101, a division plate 102 being interposed between the cylinders forming a base for cylinder 100 and an upper cylinder head for cylinder 101. Piston 105 is reciprocable in cylinder 100 and piston 106 is reciprocable in cylinder 101, the former being of less diameter and provided with a piston rod 107, while piston 106 is obviously larger and provided with a piston rod 108. By this construction, as will be obvious, the difference in effective areas is obtained by providing large and small cylinders and pistons. A duct 110 provided in the division plate 102 leads to cylinder 100, while a similar duct 111 in the division plate leads to cylinder 101. Escape ports 100^a and 101^a are provided in the cylinders 100 and 101 respectively. The air line 25, valve 26, pipe 29, branches 29^a and 29^b, and throttle valve 30 are similar to the construction in Fig. 1, for example. An exhaust pipe 28 is also provided, the same leading, however, from duct 112 in cylinder head 100^x of cylinder 100 and being in connection with the branch 28^a leading to duct 113 in cylinder head 101^x of cylinder 101.

In this embodiment of my invention, the actuating fluid is supplied to the cylinders 100 and 101 to move the pistons 105 and 106 apart, escape of air from the opposite sides of said piston being permitted through escape ports 100^a and 101^a, as will be apparent. During the return movement of the weight 43' the lesser effective area of piston 105, together with the unrestricted escape of actuating fluid through duct 110, would permit relatively rapid downward movement of the weight during the major portion of such movement. At the termination of travel of the piston 105, the movement of the weight is slowed and checked by the larger piston 106, as will be obvious, the result being similar to that accomplished by the other embodiment of my invention.

It will be apparent that my invention is susceptible of embodiment in numerous forms and modifications, and I do not wish to be restricted to the forms shown and described, except as defined in the appended claims.

What I claim is—

1. In a device of the class described, a cylinder, a pair of relatively movable pistons of lesser and greater effective areas re-

spectively, means to apply actuating fluid to the effective areas of said pistons to move a weight, and means to permit the exhaust of said actuating fluid under actuation of 5 said pistons during return movement of said weight.

2. In a device of the class described, a cylinder, a pair of relatively movable pistons of lesser and greater effective areas respectively, means to apply actuating fluid to the effective areas of said pistons to move a weight, and means to permit the exhaust of said actuating fluid under actuation of 10 said pistons during return movement of said 15 weight, one of said pistons being of relatively greater stroke than the other.

3. In a device of the class described, a cylinder, a pair of relatively movable pistons of lesser and greater effective areas respectively, means to apply actuating fluid to the effective areas of said pistons to move a weight, and means to permit the exhaust of said actuating fluid under actuation of 20 said pistons during return movement of said 25 weight, said piston of lesser effective area being of greater stroke than the other.

4. In a device of the class described, a cylinder, a pair of relatively movable pistons of lesser and greater effective areas respectively, means to apply actuating fluid to the effective areas of said pistons to move a weight, means to permit the exhaust of 30 said actuating fluid under actuation of said pistons during return movement of said 35 weight, and means to restrict the exhaust of the actuating fluid utilized to actuate one of said pistons.

5. In a device of the class described, a cylinder, a pair of relatively movable pistons of lesser and greater effective areas respectively, means to apply actuating fluid to the effective areas of said pistons to move a weight, means to permit the exhaust of said actuating fluid under actuation of said 40 pistons during return movement of said weight, and means to restrict the exhaust of the actuating fluid utilized to actuate said piston of greater effective area.

6. In a device of the class described, a cylinder, a pair of relatively movable pistons of lesser and greater effective areas respectively, means to apply actuating fluid to the effective areas of said pistons to move a weight, means to permit the exhaust of 50 said actuating fluid under actuation of said pistons during return movement of said weight, and means to restrict the exhaust of the actuating fluid utilized to actuate one of said pistons, said restricting means 55 being adjustable.

7. In a mechanism of the class described, a pair of pistons, each of said pistons being reciprocally mounted in and relative to a cylinder, one of said pistons being of relatively great effective area, means to supply 60

actuating fluid to the effective areas of said pistons to reciprocate the same, and means to permit the escape of air from opposite sides of said pistons during the fluid actuated movement thereof.

70

8. In a mechanism of the class described, a pair of pistons, each of said pistons being reciprocally mounted in and relative to a cylinder, one of said pistons being of relatively great effective area, means to supply 75 actuating fluid to the effective areas of said pistons to reciprocate the same, means to permit the escape of air from opposite sides of said pistons during the fluid actuated movement thereof, and means to permit the 80 exhaust of said actuating fluid upon the return stroke of said pistons.

9. In a mechanism of the class described, a pair of pistons, each of said pistons being reciprocally mounted in and relative to a cylinder, one of said pistons being of relatively great effective area, means to supply 85 actuating fluid to the effective areas of said pistons to reciprocate the same, means to permit the escape of air from opposite sides 90 of said pistons during the fluid actuated movement thereof, means to permit the exhaust of said actuating fluid upon the return stroke of said pistons, and means to restrict the escape of the actuating fluid during the return stroke of said piston of 95 greater effective area.

10. In a mechanism of the class described, a cylinder, a piston of relatively small effective area reciprocable in and relative to such cylinder, a second piston of relatively great effective area reciprocable in and relative to 100 said cylinder, said first named piston being of greater stroke, a fluid actuating supply line, ducts leading therefrom to said cylinder to supply actuating fluid to the effective areas of said pistons, an exhaust duct leading from said cylinder between said pistons, and a valve means operable to throw said ducts into communication with the fluid supply 105 line or with said exhaust means.

11. In a mechanism of the class described, a cylinder, a piston of relatively small effective area reciprocable in and relative to such cylinder, a second piston of relatively great effective area reciprocable in and relative to 115 said cylinder, said first named piston being of greater stroke, a fluid actuating supply line, ducts leading therefrom to said cylinder to supply actuating fluid to the effective areas of said pistons, an exhaust duct leading from said cylinder between said pistons, a valve means operable to throw said ducts into communication with the fluid supply 120 line or with said exhaust means, and means to restrict the exhaust of the actuating fluid from said cylinder beneath said piston of greater area.

12. In a mechanism of the class described, a cylinder, a piston of relatively small ef- 130

fective area reciprocable therein and relative thereto, a second piston of relatively great area reciprocable therein and relative thereto, said first named piston being of relatively great stroke, a fluid supply line, ducts leading therefrom to said cylinder, a supply actuating fluid to actuate said pistons, a throttle valve mounted in one of said ducts to restrict the flow of actuating fluid from beneath said piston of greater effective area, an exhaust duct leading from said cylinder between said pistons, and means to throw said exhaust duct into communication with said fluid supply ducts, said means being operable to cut out said communication and throw said supply ducts into communication with said fluid supply line.

13. In a mechanism of the class described, a cylinder, a piston of relatively small effective area reciprocable therein and relative thereto, a second piston of relatively

great area reciprocable therein and relative thereto, said first named piston being of relatively great stroke, a fluid supply line, ducts leading therefrom to said cylinder, a supply actuating fluid to actuate said pistons, a throttle valve mounted in one of said ducts to restrict the flow of actuating fluid from beneath said piston of greater effective area, an exhaust duct leading from said cylinder between said pistons, and means to throw said exhaust duct into communication with said fluid supply ducts, said means being operable to cut out said communication and throw said supply ducts into communication with said fluid supply line, said cylinder being provided with an escape port between said pistons.

In testimony whereof, I have subscribed my name.

JOHN C. HANNA.
